SAFETY STIRRUP

Thomas C. Evans, Russell, Kans.

Application December 26, 1950, Serial No. 202,585

2 Claims. (Cl. 54—49)

1

This invention relates to a safety stirrup for use in riding horses.

This invention is an improvement over the safety stirrup shown and described in my Patent No. 1,129,655, dated February 23, 1915.

The object of the invention is to provide a safety stirrup which is constructed so that it will be readily disconnected from the saddle or stirrup strap in the event the rider is thrown from the horse, so that there will be no danger of having his foot entangled in the stirrup and consequently being dragged along the ground by the animal.

Another object of the invention is to provide a safety stirrup which will be automatically released from a stirrup strap should the rider of the horse be thrown and catch his foot in the stirrup, the strap of the present invention being provided with springs which will prevent the strap from accidentally working loose from the stirrup strap, there being a means for maintaining the trip mechanism in its open position.

A further object of the invention is to provide a stirrup strap which is extremely simple and inexpensive to manufacture.

Other objects and advantages of the invention will be apparent during the course of the following description.

In the accompanying drawings forming a part of this application, and in which like numerals are used to designate like parts throughout the same:

Figure 1 is a side elevational view of the stirrup constructed according to the present invention;

Figure 2 is an end elevational view of the stirrup;

Figure 3 is a sectional view taken on the line 3—3 of Figure 1;

Figure 4 is a fragmentary sectional view similar to Figure 3, but showing the position of the parts in open position;

Figure 5 is a view similar to Figure 2, but showing the position of the parts when the stirrup is disconnected;

Figure 6 is a sectional view taken on the line 6—6 of Figure 4;

Figure 7 is a fragmentary elevational view showing the connection of the stirrup strap to the sleeve.

Referring in detail to the drawings, the numeral 1 designates a stirrup which may be fabricated of any suitable material. The side arms of the stirrup, adjacent their upper edges, are provided with slots or depressions 2, the depressions adapted to receive therein the removable rod 3. The rod 3 preferably has both of its ends

threaded for the reception of nuts 4, whereby the ends of the stirrup, or the side arms thereof, will be maintained in proper spaced relation with respect to each other. The rod 3 is centrally provided with a sleeve 5, the sleeve 5 adapted to receive the saddle or stirrup strap 6, Figures 2 and 7.

The numeral 7 designates the main connecting bar for the side arms of the stirrup. This bar passes through suitable openings in said side arms, and the opposite ends of the bar are threaded, as at 8, the threaded portions 8 adapted to receive suitable nuts 9, whereby the side arms of the stirrup may be adjusted toward or away from each other as desired.

The numeral 10 designates the yoke for the device. This yoke is of substantially U-shaped formation and has its side arms provided with openings through which pass the securing rods 7 for the arms of the stirrup. The yoke is mounted for rotation upon the securing rod 7 and the upper extremities of the arms of the yoke are formed with slots or depressions 12, which, when the yoke is rotated in one direction, are adapted to engage with the rod 3 adjacent the opposite ends of the sleeve 5. The connecting member 11 of the yoke is arched and is arranged at an angular relation to the side arms of the yoke so that one of the edges of the connecting member is projected a suitable distance beyond the side arms of the yoke. This projecting portion is adapted to serve as an abutment for the toe of the boot of the rider when the rider's mount becomes unmanageable, and whereby the yoke will be rotated so as to bring its engaging portions away from the rod 3 to permit the stirrup to be removed or disconnected from the rod 3 and from the saddle strap.

The safety stirrup of the present invention is threaded through a pair of springs 14 each of which has its upper end arranged in engagement with a slot 15, Figures 3 and 4, in the top of the stirrup 1, and a collar 16 is circumscribed on the fulcrum bar 7 and interposed between the pair of springs 14. The opposite or lower end of the springs 14 are bent, as at 13, and engage the connecting member 11 of the yoke 10, the springs 14 serving to hold the yoke in position and preventing it from slipping back and releasing the stirrup until weight is thrown against it. This is a definite improvement over the stirrup of my Patent No. 1,129,655, since the stirrup shown in my patent has a tendency to work loose on the mere pressure of the rider's foot in the stirrup. In other words, my patented stirrup depended

upon friction to hold the yoke in place, while in the present invention the yoke is held in place by the springs 14.

There is further provided a spring 17 which may be made of round or flat spring steel, and the spring 17 is connected to the yoke 10 by a suitable securing element, such as the rivet 18. The free end of the spring 17 is adapted to project through a slot 20 in the yoke, whereby the transverse end 19, or free end, of the spring 17 can engage the inside of the stirrup to thereby selectively lock the trip mechanism in its open position. Thus, when the stirrup is tripped, the yoke expands and will move beyond the edge of the stirrup and the end 19 of the spring 17 protrudes or extends through the slot 20, beyond the edge of the stirrup. This feature makes it easier to again connect the apparatus after it has been tripped. Without this feature, it is difficult to fasten the straps to the rod 3.

Arranged on each end of the rod 3 is a plate 21, the plates 21 being each provided with a rectangular cutout or slot 22 for receiving therein the nut 9. This position of the plates 21 with the slots 22 insures that the parts will be properly aligned.

From the foregoing it is apparent that a safety stirrup has been provided which is constructed so that by manipulating the foot of the rider, the stirrup will easily and quickly become disconnected from the stirrup straps. Thus, in the event that the rider of the horse is thrown to the ground, there will be no danger of having his foot entangled in the stirrup and consequently being dragged along the ground by the animal. The springs 14 of the stirrup prevent the yoke from accidentally rotating or pivoting, and the spring 17 serves to lock the trip mechanism in open position.

I claim:

1. In combination, a stirrup having side arms provided with first slots at the upper edges thereof and second slots in said side arms below and at an angle to said first slots, a bar connecting the side arms together and located below and in vertical alignment with said first slots, a collar circumscribed on said bar with its ends spaced from the inner faces of said side arms a rod seated in said first slots, a sleeve on said rod having its ends spaced from the inner faces of said side arms, and a U-shaped yoke rotatable within the arms and journaled upon said bar, said yoke including side arms provided with slots for receiving said rod, said yoke in-

cluding an arched connecting member, and resilient means for preventing accidental rotation of said yoke, said resilient means embodying a pair of springs circumscribed on said bar between the opposite ends of the collar and the inner faces of the side arms and said springs having their upper ends engaging in the second slots in the side arms of the said stirrup and their lower ends engaging the connecting member of the yoke, there being a slot in one of the side members of said yoke, and a flat spring secured to said yoke and having a transverse end for projecting through said slot.

2. In combination, a stirrup having side arms provided with first slots at the upper edges thereof and second slots in said side arms below and at an angle to said first slots, a bar connecting the side arms together and located below and in vertical alignment with said first slots, a collar circumscribed on said bar with its ends spaced from the inner faces of said side arms a rod seated in said first slots, a sleeve on said rod having its ends spaced from the inner faces of said side arms, a U-shaped yoke rotatable within the arms and journaled upon said bar, said yoke including side arms provided with slots for receiving said rod, said yoke including an arched connecting member, resilient means for preventing accidental rotation of said yoke, said resilient means embodying a pair of springs circumscribed on said bar between the opposite ends of the collar and the inner faces of the side arms and said springs having their upper ends engaging in the second slots in the side arms of the said stirrup and their lower ends engaging the connecting member of the yoke, there being a slot in one of the side members of said yoke, a flat spring secured to said yoke and having a transverse end for projecting through said slot, and plates mounted on the ends of said rods for maintaining the parts in alignment.

THOMAS C. EVANS.
